UNITED STATES PATENT OFFICE.

HANS JENS MEYER, OF ALTONA, GERMANY.

ADJUSTING DEVICE FOR PATTERN-CYLINDERS OF PRINTING-MACHINES.

1,159,243.

Specification of Letters Patent.

Patented Nov. 2, 1915.

Application filed June 29, 1914. Serial No. 848,067.

To all whom it may concern:

Be it known that I, HANS JENS MEYER, mechanical engineer, subject of the German Empérör, and resident of No. 239 Schützenstrasse, Altona-on-the-Elbe, Germany, have invented new and useful Improvements in Adjusting Devices for Pattern-Cylinders of Printing-Machines, of which the following is a specification.

- 10 The present invention relates to an improvement on the device for adjusting the pattern cylinders of machines for printing upon webs of paper or fabric as described in the specification of Letters Patent No. 1083543.
- 15 According to the invention a pointed mandrel is used for adjusting the pattern-cylinders, the mandrel being connected to carriages of the respective color mechanisms which are moved at the same time as the corresponding pattern-cylinders, and in the ratio of 2:1 as set forth in the specification of Letters Patent No. 877570. The pointed mandrel is used for the purpose of bringing opposite the point of the mandrel certain points of the pattern-cylinders, for example the points at which the patterns begin, the so-called "Picot," so that the pattern cylinders can be accurately adjusted successively both transversely and longitudinally to the pattern. In order that the pointed mandrel may be used for successively adjusting any suitable number of pattern-cylinders accurately, whatever may be the diameters of these cylinders, a small support is secured to the carriage of each color mechanism, which must be capable of adjustment on the machine both transversely and longitudinally to the web of paper or fabric to be printed upon, so that the point of the mandrel, the axis of the pattern-cylinder and the axis of the impression-cylinder are made to lie in a straight line. It is thus possible to use the device according to the American specification 877570 for adjusting the pattern-cylinders, as then the movement of the pointed mandrel must accurately correspond with the movement of the color mechanism and pattern-cylinder in the ratio 2:1 no matter what the diameter of the pattern-cylinders may be.

By the use of a rib on the pattern-cylinder and a mandrel, toward which the rib of the pattern-cylinder is turned, inaccuracies may be caused because a small error, which occurs when adjusting pattern-cylinders of

small diameter, will increase when pattern-cylinders of larger diameter are to be adjusted, as the mandrel when using small and large pattern-cylinders must always be the same distance from the central axis thereof and consequently the rib must also be secured to the pattern-cylinder. To obviate this disadvantage the mandrel toward which the pattern cylinder was turned according to German Patent No. 227704/8c is replaced by a pointed mandrel, which permits of an adjustment of the point in question directly in the peripheral line, whereby the accurate adjustment can be immediately effected which was not the case with the previously known device. Consequently the regulator hitherto necessary for overcoming small errors could be entirely dispensed with if the die sinker would accurately bring forward the starting point of the pattern (Picot) on each cylinder.

According to the present invention the adjustment of the central wheel or disk by a pin or mandrel is omitted for practical reasons, and this arrangement is replaced by marks on the central wheel arranged according to the angular distance between the pattern cylinders and adjusted successively to register with a fixed mark on the frame.

In the accompanying drawing, Figure 1 shows a plan, Fig. 2 shows a side elevation and Fig. 3 shows a front elevation of the new device. Fig. 4 is a detail section taken on the line 4—4 of Fig. 1. Fig. 5 is a similar view showing a different position of the mechanism. Fig. 6 is an enlarged detail side elevation of the mandrel and its correlated parts. Fig. 7 is a detail section taken on the line 7—7 of Fig. 6. Fig. 8 is a detail section taken on the line 8—8 of Fig. 7. Fig. 9 is a detail section taken on the line 9—9 of Fig. 8. Fig. 10 is a detail section taken on the line 10—10 of Fig. 1.

The periphery of the central disk *b* on the shaft of the impression-cylinder is provided with as many marks I, II, III, IV as there are colors or pattern-cylinders *e'*, *e²*, *e³*, *e⁴*. The distance between these marks, in angular measure, corresponds to the distance between the pattern-cylinders. The marks are on members *z* which are adjusted in the required angular positions upon the central disk *b*. On the machine frame *M* is rigidly secured an arm *y* of which the front end passes over the central disk *b* and carries the

counter-mark (stroke) X. The marks I, II, III, IV are successively adjusted to the counter-mark X. The carriages *g* and *s* for supporting and receiving the pattern-cylinders and color mechanism respectively are connected together by gearing according to the specification of Letters Patent No. 877570 in such a manner that the color mechanism and the pattern-cylinder are moved 5 at the ratio 2:1. In one of the carriages *s* of each color mechanism is mounted a support *t* adapted to receive the mandrel *u* which at its free end is provided with an adjustable bolt *u*² having a point *u*². The support *t* is 10 adjustable on the carriage both transversely and longitudinally, and is so adjusted that the point *u*² of the mandrel *u*, the axis of the pattern-cylinder and the axis of the impression-cylinders lie in a straight line, as 15 20 will be clearly seen in Fig. 2. The mandrel *u* is inserted into one of these supports *t*, and is so retained therein that it cannot turn. When inserted it abuts against an adjustable plate *v* in the base of the support.

25 Extending from the side of the support *t*, is an attaching ear *t*', and adjacent and between the said ear and the support *s*, is an intermediate adjusting block *s*', a screw *t*², is threaded into the blocks *s*' and its head 30 end extends into a recess *t*³, the screw *t*², has a roller *t*⁴, mounted thereon and the roller is adapted to engage a recess *t*⁵, in the block *t*. In the same manner a screw *s*², is 35 threaded into the side of the support *s*, a roller *s*³, is mounted on the screw, said roller operating in a recess *s*⁴. It will be seen that if the screw *t*², is rotated, the support *t*, will 40 be moved vertically by reason of the engagement of the screw with the block, and correspondingly if the screw *s*², is turned a lateral movement will be imparted to the block *s*', and the support *t*, carried thereby.

45 For the purpose of securing longitudinal adjustment a bolt *v* is threaded into the support *t*, and bears against the inner end of the mandrel, as clearly illustrated in Fig. 8, a jam nut *v*' serves to hold the bolt against turning. For securing a rough adjustment 50 of the mandrel, a vertical slot is formed in the ear *t*', as indicated at *t*⁶, and a horizontal slot is similarly formed in the carriage *s*, as indicated at *s*⁶, the bolt *t*', is adapted to pass through these slots and a certain latitude of adjustment of the support *t*, and block *s*', is thus permitted and they may be held by 55 the tightening of the nut on the bolt *t*'.

60 After the adjustment of the pattern cylinder has been made, it will be necessary to secure it in its adjusted position, therefore a collar *o*, is provided surrounding the pattern cylinder shaft and secured at one side by a screw *o*', a square headed bolt *o*² serves to clamp the collar to the shaft, and as the collar is fastened to the carriage *g*, the shaft 65 will be held against rotation. For the pur-

pose of accommodating various sizes of pattern cylinders, a mechanism is illustrated which however, forms no part of this invention, the carriages *s* and *g* are mounted for sliding movement on the frame *M*, a worm shaft and worm 2 are journaled in the frame and are adapted to mesh with a worm wheel 3, said wheel is mounted on a shaft 4, which is also journaled in the frame. Pinions 5 and 7 are also mounted on the shaft 4 and pinion 5 engages a rack bar 6, forming a part of carriage *s*, while the pinion 7 meshes with an idler 8, which is journaled in the frame, a pinion 9 engages the idler 8 and also a rack 10, which forms a 70 part of the carriage *g*, a hand wheel 11 is secured to the worm shaft 2. It will thus be seen that upon operating the hand wheel, the carriages *s* and *g*, will be moved toward or away from the impression cylinder with a speed ratio of 2:1 respectively. Various diameters of pattern cylinder may be inserted and the mandrel point *u*² will be found to always be in a position to coincide with the point *w*, when the starting points 75 of the pattern and impression cylinder are in contact.

80 When the mark I has been adjusted to the counter-mark X, the mandrel is inserted into the support *t* mounted in the carriage *s* of the color mechanism opposite the pattern-cylinder *e*' which is to be adjusted first. The point *u*² of the bolt *u* mounted in the mandrel *u* is directed exactly radial to the periphery of the pattern-cylinder *e*'. This is now turned and moved by means of the hand lever *p* until the point *w*, which for example indicates the beginning of the pattern (Picot), is opposite the point *u*². When this has been done the shaft 100 of the pattern-cylinder is locked by the coupling *o*. The pattern-cylinder *e*' is now adjusted. The mandrel *u* is now withdrawn from the support *t* and inserted into the support *t* of the next color mechanism, while the central disk *b* is turned until its mark II is opposite the mark X, and the operation as hereinbefore described is repeated. This 105 operation is repeated for each pattern-cylinder.

110 Having thus described my invention what I claim as new and desire to secure by Letters Patent is:—

1. The combination with the impression and pattern cylinders and the color mechanism of a printing machine, of means mounted on the impression cylinder for indicating the leading ends of the impression surface, and means movable with the color mechanism for indicating the leading end 115 of the pattern cylinder surface.

2. The combination with the impression and pattern cylinders and color mechanism of a rotary printing machine including 120 means for varying in ratio the distance be-

5 between the pattern and impression cylinder and the pattern cylinder and color band carriage, of means movable with the color band carriage for indicating the leading end of the pattern surface, said indicating means being adjustable vertically, longitudinally and laterally.

10 3. A device for adjusting the pattern cylinders of rotary printing machines comprising a mandrel mounted on the color band carriage, means for adjusting the mandrel vertically, horizontally and laterally, and a pointer on said mandrel for registration with the leading end of the pattern cylinder 15 surface.

20 4. A device for adjusting the pattern cylinders of a rotary printing machine comprising a mandrel, a support for said mandrel, a movable block, and means for clamping the support and movable block to the pattern carriage, means for moving the block laterally on the carriage, and means for moving the mandrel support vertically on the block.

25 5. A device for adjusting the pattern cylinders of a rotary printing machine, comprising a mandrel, a support having a socket in which the mandrel is adapted to engage, an adjusting screw in said support for engagement with the mandrel, an ear formed 30 on the support and extending at a right angle thereto, a block, a bolt for clamping the ear and block to the pattern cylinder carriage, means for moving the ear and support vertically, and means for moving the 35 block, ear and support horizontally.

40 6. In a rotary printing machine having an impression-cylinder, a plurality of pattern-cylinders disposed around said impression-cylinder and carriages with color mechanisms, and driving mechanism therefor, the combination with the impression - cylinder and the pattern-cylinders of a disk on the shaft of the impression-cylinder and having marks thereon, said marks being the same

45 angular distances apart as the pattern-cylinders, a stationary index with which the marks on the cylinder are adapted to be brought successively into register, a pointed mandrel adapted to be mounted successively 50 on the carriages, means for adjusting the mandrel and pattern - cylinder so that the mandrel point will lie adjacent the beginning of the pattern on the pattern-cylinder, and so that the mandrel, the axis of the pattern-cylinder and the axis of the impression-cylinder will be in alinement in the position 55 of adjustment.

60 7. In a rotary printing machine having an impression-cylinder, a plurality of pattern-cylinders disposed around the impression-cylinder and carriages with color mechanism, and driving mechanism therefor, the combination with the impression cylinder and the pattern-cylinders of a disk, said 65 disk being mounted on the shaft of the im-

pression cylinder and having marks thereon at the same angular distances apart as the pattern - cylinders, a stationary index with which the marks on the disk are adapted to be brought successively into register, a support mounted on each of the carriages, a pointed mandrel, adapted to be mounted successively in the supports, said pointed mandrel being adapted to be brought adjacent the beginning of the pattern on the pattern-cylinders when the corresponding mark on the disk is opposite the stationary index whereby the pointed mandrel, the axis of the pattern-cylinder and the axis of the impression-cylinder will be brought into a straight line in the position of adjustment, and means for locking the pattern-cylinder after adjustment.

70 8. In a rotary printing machine having an impression - cylinder, a plurality of pattern-cylinders disposed around the impression-cylinder and carriages with color mechanism, and driving mechanism therefor, the combination with the impression - cylinder and the pattern-cylinders or a disk mounted 75 on the shaft of the impression-cylinder, said disks having marks thereon at the same angular distances apart as the pattern-cylinders, a stationary index with which the marks on the disk are adapted to be brought 80 successively into register, a support mounted on each of the carriages, a pointed mandrel adapted to be mounted successively in the supports, means for adjusting the mandrel in the supports while preventing it from 85 turning, means for moving said supports radially and transversely on the carriages so as to bring the pointed mandrel adjacent the beginning of the pattern on the pattern-cylinder, whereby the printed mandrel, the 90 axis of the pattern-cylinder and the axis of the impression - cylinder are brought into alinement, and means for locking the pattern-cylinders after adjustment.

95 9. In a rotary printing machine having an impression-cylinder, four pattern-cylinders disposed around said impression - cylinder, four carriages, one adjacent each pattern-cylinder, adapted to carry the color mechanism, and driving mechanism therefor, the combination with the impression - cylinder and the four pattern-cylinders, of a disk 100 turning with the impression-cylinder, four markers thereon with marks in angular positions corresponding to those of the four pattern-cylinders, a stationary marker with which the marks on the disk are adapted to be brought successively into register, a support attached to each carriage, a mandrel with a pointed member thereon, said mandrel being adapted to be applied successively 105 to the supports on the respective carriages, and means for adjusting the mandrel and the pattern-cylinder while the disk is in one 110 of its settings in order to bring the mandrel 115 120 125 130

point into register with a particular point on the pattern-cylinder, whereby the mandrel point, the axis of the pattern-cylinder, and the axis of the impression-cylinder are brought all into alinement.

In testimony whereof I have signed my name to this specification in the presence of

two subscribing witnesses this 17th day of June, 1914.

HANS JENS MEYER.
